HERBERT F. PROVANDIE, OF MELROSE, MASSACHUSETTS, ASSIGNOR TO AMERICAN WATER SUPPLY COMPANY OF NEW ENGLAND, OF BOSTON, MASSACHUSETTS, A CORPORATION OF MASSACHUSETTS.

PAPER DRINKING-CUP.

1,125,171.

Specification of Letters Patent.

Patented Jan. 19, 1915.

Application filed April 29, 1913. Serial No. 764,318.

To all whom it may concern:

Be it known that I, HERBERT F. PROVANDIE, a citizen of the United States, residing at Melrose, in the county of Middlesex and 5 State of Massachusetts, have invented an Improvement in Paper Drinking-Cups, of which the following is a specification.

This invention relates to paper drinking-cups, and has for its object to construct a 10 cup of a single small piece of paper which shall be water-tight and which may or may not have an integrally formed tab at the side to serve as a handle.

Various forms of drinking-cups have been 15 made composed of a single piece of paper but they have usually been made of a much larger piece of paper than is necessary, which is folded in various ways and these folds are adhesively secured together, the 20 object being to produce a water-tight cup.

In accordance with the present invention a segmental piece of paper is employed which is bent or folded to form a conical cup, and one of the radial sides of the segment 25 extends to a different center from the other radial side, thereby to form a shoulder at the junction of the two radial sides, so that the side portion having the shoulder will be extended to form an overlapping 30 portion to overlap the other side portion and tightly close the apex of the cup. If the two radial sides are alike such an overlapping portion will not be formed and the apex of the cup will not be tightly closed. 35 On the overlapping side portion of the blank a tab is or may be integrally formed which is adapted to serve as a handle for holding the cup. When the segmental blank is bent to form a conical cup, the cups thus formed 40 may be nested together, and when said blank is folded the cups will be collapsed.

Figure 1 is a side elevation of a paper drinking-cup embodying this invention. Fig. 2 is a plan view of the same. Fig. 3 45 is a side elevation of a folded paper drinking-cup embodying this invention, the same being collapsed. Fig. 4 is an edge view of the cup shown in Fig. 3. Fig. 5 is a plan view of the cup shown in Fig. 3 expanded. 50 Fig. 6 is a view of the segmental blank composing the cup, the dotted lines representing the overlapping portion and lines of fold.

10 represents a segmental blank which in-

cludes considerably less than one-half a 55 circle. One of the radial sides, as 12, of the blank extends to a point or center 13, and the other non-radial side, as 15, extends to a point or center 14 below the point or center 16 which is in line with the line of fold 60 14, which is below the point or center 13, so that the shoulder 17 is formed, which is arranged at an angle with respect to both radial sides. Said shoulder serves as one end of an overlapping portion which is 65 indicated by the portion between said radial side 15 and the dotted line 20.

A tab 25 of any suitable shape, and here shown as semi-circular, is or may be formed integral with the blank on the radial side 15. 70 In practice it is preferred to employ such tab as it is well suited to serve as a handle at the side of the cup. In forming the cup the segmental blank thus cut is bent as in Figs. 1 and 2, or folded as in Figs. 3 and 4, 75 so that the overlapping portion extends over the outside of the other side portion of the blank, the overlap being determined by the length of the shoulder 17, at the bottom or apex of the cup and extended from said 80 shoulder in a radial direction to the outer edge of the blank, as represented by dotted line 20, so that the overlapping portion is wider at the outer end than at the inner end. The apex of the cup is thus tightly 85 closed, and as a result the cup is water-tight. The segmental blank of which the cup is made may be composed of paper coated with paraffin-wax, or the cup, when completed, may be coated with paraffin-wax. The tab, 90 although flexible, is stiff enough to hold the small weight of water contained in the cup; and it is adapted to be laid against the side of the cup, so that a plurality of cups may be nested, or in case the cup is folded, so 95 that a plurality of cups may be superimposed. In the case of the folded cup it will be seen that such a cup is expanded and filled, V-shape portions are formed at the front, and rear, so that a user when placing 100 his lips to the cup to drink, the tab will be disposed at the side of the cup.

I claim:

A blank for forming drinking cups comprising a section of material having a curved 105 edge and opposing straight edges, the curved edge being of less than semi-circular length, one of said straight edges being radial to

said circular edge, the other of said straight edges being parallel throughout to a radius and having an end portion at an angle to the radial edge, the material of said parallel edge being projected to form a tab, the blank being assembled in conical formation and the material adjacent the parallel edge being fully and completely overlapped with one of said straight edges being radial to form a double juncture at the bottom and

permit manipulation of the tab without interfering with the sealing juncture.

In testimony whereof, I have signed my name to this specification, in the presence of two subscribing witnesses.

HERBERT F. PROVANDIE.
